assignor to

North, Harrison & Chase.

Letters Patent No. 422. Dated Nov. 11. 1857.

The schedule referred to in these Letters Patent, & making part of the same.

To all whom it may concern:

Be it known that I, S. W. Gibbs, of Albany, in the county of Albany & state of New York, have invented or produced a new design for stoves, and I do hereby declare that the following is a full & exact description of the same.

(The design consists in the application of certain ornaments to cast iron plates, which are intended for

Nes 1862

coal stoves. These ornaments & the general configuration of the plates, are represented in the model & also in the accompanying drawings, to which I make the following references, viz:

- Fig. 1, represents a front elevation of the completed stove.
 Fig. 2, " a lateral elevation " " "
 Fig. 3, " a back elevation " " "
 Fig. 4, " a bird's Eye view of the top & cover.
 Fig. 5, " the bottom plate.
 Fig. 6, " the moulding of the hearth plate
 and hearth damper.
 Fig. 7, " the moulding of the top plate &
 cover.
 Fig. 8, " the ornamental border of the top plate.
 Fig. 9, " the foot which however, is no part of my design.
 a, " the moulding represented in fig. 7.
 b, " the hearth damper.
 C, " the ornamental border represented in
 fig. 8.

The design of the cover & foot, not being original with me, I do not claim them as any part of my invention, except when they are used in combination with the parts of my design above referred to.

What I claim as my invention and desire to secure by Letters Patent, is the ornamental design for a stove, as herein described and as represented in the annexed drawings.

Witnesses,

John Crump
Augustus T. Jones

S. W. Gibbs.
